UNITED STATES PATENT OFFICE.

RIDDLE D. HAWORTH, OF PITTSBURGH, PENNSYLVANIA, ASSIGNOR TO HAWORTH & DEWHURST, LIMITED, OF PITTSBURGH, PENNSYLVANIA, A PARTNERSHIP COMPOSED OF RIDDLE D. HAWORTH, J. FRED HAWORTH, AND A. R. DARRAGH.

DESIGN FOR A FLYING TOY.

59,419.

Specification for Design.

Patented Oct. 18, 1921.

Application filed June 28, 1920. Serial No. 392,527. Term of patent 3½ years.

To all whom it may concern:

Be it known that I, RIDDLE D. HAWORTH, a citizen of the United States, residing at Pittsburgh, in the county of Allegheny and State of Pennsylvania, have invented a new, original, and ornamental Design for a Flying Toy, of which the following is a specification, reference being had to the accompanying drawing, forming part thereof, in which—

Figure 1 is a view in perspective showing my new design.

Fig. 2 is a view in front elevation.

Fig. 3 is a view of the blank from which my design for a flying toy is made up.

I claim:

The ornamental design for a flying toy as shown.

RIDDLE D. HAWORTH.
